UNITED STATES PATENT OFFICE.

ADRIAN F. WOLFF, OF WATERBURY, CONNECTICUT, ASSIGNOR TO SCOVILL MANUFACTURING COMPANY, OF WATERBURY, CONNECTICUT, A CORPORATION OF CONNECTICUT.

POWDER-CAN TOP.

No. 853,141.

Specification of Letters Patent.

Patented May 7, 1907.

Application filed February 16, 1906. Serial No. 301,399.

To all whom it may concern:

Be it known that I, ADRIAN F. WOLFF, a citizen of the United States, residing at Waterbury, in the county of New Haven and State of Connecticut, have invented a certain new and useful Improvement in Powder-Can Tops, of which the following is a full, clear, and exact description.

This invention relates to the class of cans or similar receptacles for containing powdery substances, which are to be dispensed through a hole or holes in the top, and including means for opening and closing the hole or holes as desired. Such tops have been used on cans and other receptacles for toilet powder and other like impalpable powders, but there is always more or less waste or undesirable escape of the powder between the constituent shells of the top, due to the loose fitting of these shells; and it is the object of the present invention to fit the shells together so tightly as to obviate this undesirable escape of the powdery contents of the receptacle, without impairing the freedom of movement of the movable shell.

The invention consists of a powder can top, of the class described, comprising a fixed shell properly perforated for the escape of the powder, and a movable shell also perforated so that its hole or holes may be brought into register with the hole or holes in the fixed shell to permit the desired escape of the powder, the two shells being united by a rivet which serves as an axis upon which the movable shell turns, and this rivet being headed up on a spring washer on the fixed shell, in such way that the spring washer constantly maintains tension upon the rivet sufficient to draw the movable shell into such intimate contact with the fixed shell as to prevent the escape and consequent waste of the powder when the top is purposely closed, and also in such way as not to interfere with the freedom of movement of the movable shell, all as I will proceed now more particularly to set forth and finally claim.

In the accompanying drawings illustrating the invention, in the several figures of which like parts are similarly designated, Figure 1 is a top plan view, illustrating my invention as applied to a powder can top having a sin-

gle opening, the parts being shown with the opening uncovered. Fig. 2 is a side elevation. Fig. 3 is a vertical cross-section.

1 is the breast of the can or receptacle, of any suitable shape, and 2 is the fixed shell of the top applied to the breast in any suitable manner, as by a folded joint 3. This shell 2 has any suitable number and arrangement of dispensing holes, but for purposes of illustration, I have shown a single relatively large hole 4. The shell is also provided with a struck-up stop-lug 5. The center of the shell 2 has an inwardly projecting portion or depression 6, of substantially elliptical form, and provided with a central perforation. This depression 6 constitutes the spring or washer or spring-washer herein referred to. The outer movable shell 7 has a circumferential flange 8 embracing the vertical wall of the fixed shell and milled, knurled or otherwise roughened to afford a finger-grasp for turning the said shell. A hole or holes 9 is or are made in the movable shell to register with the hole or holes 4 in the fixed shell. The shell 7 is also provided with a segmental slot 10 which cooperates with the stop-lug 5 to limit the extent of rotation of the movable shell with relation to the fixed shell. A central perforation is made in the movable shell to register with the hole in the washer 6 in the fixed shell, and the two shells, being arranged as in the drawings, are then united by a rivet 11 whose shank is passed through the central perforations and upset or clenched at 12 against the inner face of the washer 6. Inasmuch as the metal of such tops is thin, the washer 6 serves as a spring, drawing upon the rivet 11 to hold the movable shell in such intimate contact with the inner or fixed shell as to obviate the leakage and waste of the powdery contents of the receptacle, and yet not to interfere at all with the freedom of movement of the outer shell in bringing its hole or holes into and out of register with the hole or holes of the fixed shell.

The washer 6 is most economically made as an integral part of the fixed shell, by depressing the central portion thereof, as shown, although the invention might be carried out by using a separate spring-washer.

As already indicated, the washer-like projection acts as a sort of spring, and thereby

enables the rivet to hold the outer shell tight down upon and against the inner shell, so as to make a practically perfect seal to prevent the escape of the powder, and at the same time it insures a smooth working fit between the parts.

What I claim is:—

1. A powder can top, comprising a perforated fixed shell having a central washer-like portion serving as a spring, an outer movable shell applied externally to and supported directly upon the fixed shell, and a rivet passed through the two shells and the washer-like portion and headed up against the inner side of said portion so as to hold the outer shell in intimate contact with the inner shell and serving as an axis for the outer shell to per-

mit its rotation on the inner shell to cover and uncover the perforation therein.

2. A powder can top, comprising a perforated fixed shell, having a central integral washer-like perforated depression, an outer movable shell applied to the fixed shell, and a rivet passed through the two shells and the depression and clenched or headed up against the inner side of the washer-like depression so as to hold the outer shell in intimate contact with the inner shell.

In testimony whereof I have hereunto set my hand this 15th day of February A.D. 1906.

ADRIAN F. WOLFF.
